UNITED STATES PATENT OFFICE

2,185,428

ROTARY ENGINE

Rene Arthur Brunet, Charleston, W. Va.

Application January 28, 1938, Serial No. 187,517

1 Claim. (Cl. 121—77)

This invention appertains to new and useful improvements in engines and more particularly to an engine or motor adapted to be operated by compressed fluid.

5 The principal object of the present invention is to provide a fluid operated engine wherein the parts are positive acting and not susceptible to the ready development of defects.

Another important object of the invention is 10 to provide a compressed fluid operated engine, the rotation of which can be reversed quickly and efficiently.

Still another important object of the invention is to provide an engine of the character stated 15 wherein the parts are of simple construction and assembled in an accessible and practical manner.

Other important objects and advantages of the invention will become apparent to the reader 20 of the following specification.

In the drawings:

Figure 1 represents a side elevational view of the engine.

Figure 2 is a vertical sectional view through 25 the engine taken on the line 2—2 of Figure 1.

Figure 3 is a side elevational view of the engine with one side wall removed and the pipes on the approach side in section.

Figure 4 is a fragmentary detailed sectional 30 view taken on the line 4—4 of Figure 2.

Figure 5 is an inside elevational view of one side wall of the stator.

Referring to the drawings wherein like numerals designate like parts, it can be seen that the 35 stator is generally referred to by numeral 5 and the rotor by numeral 6. The stator consists of the cylindrical wall structure 7 and the two end wall structures 8—9, one of which is preferably removable to permit access to the interior of the 40 stator.

At the proper intervals around the circumference of the cylinder 7 are outstanding cases 10 in each of which is the slidable abutment 11 operating between anti-friction rollers 12. A 45 spring 13 in each of the cases 10 serves to urge the corresponding abutment 11 toward the rotor 6, so that it will ride against the periphery of the rotor and into the pocket 14. The ends of the pocket are sloped as at 15 to facilitate entrance and exit of the abutment with respect to 50 the pocket.

Each side of the engine is provided with a supply pipe and an exhaust pipe. On one side of the engine is the compressed fluid supply pipe 16 55 which is of annular formation as is the cor-

responding exhaust pipe 17. On the other side of the engine is the supply pipe 18 and the exhaust pipe 19. Extending to the pipe 16 is the supply pipe 18 and from the pipe 17 extends the pipe 19' and in these pipes are the valves 20—21, respectively, connected by the link 22 and operated by the handle 23.

From the pipes 18—19 extend the pipes 24—25 in which are the valves 26—27 connected by the link 28 and operated by the handle 29 in unison. 10

As is shown in Figure 3, the pipe 16 is provided with branch extensions 30 which extend into the stator 7 and deliver compressed fluid into the pocket on the left sides of the abutments 11. The rotor 6 is provided with ports 15 31, one for each of the pockets 14 and with these pockets are registerable the grooves 32 in the side wall 9 from which grooveways extend the branch pipes 33 to the exhaust pipe 17. Thus it can be seen, that while compressed 20 fluid is being supplied to the left side of the top abutment in Figure 3 so that the rotor 6 is being moved in the direction of the arrow, fluid in the pocket at the right side of the abutment 11 is escaping by way of the adjacent port 31, 25 groove 32 and pipe 17.

When a reverse rotation of the engine is desired, compressed fluid is supplied from the pipe 18 by way of the branch pipes 34, which result in movement of the rotor in the opposite direction while air behind the abutment is escaping by way of the ports 35 and stator grooves 36 to the pipe 19. This reversing operation is obtained by closing the first set of valves shown in Figure 1 and opening the second set, thus 35 changing the delivery of compressed fluid from one side of the abutment to the opposite side.

Numerals 37 denotes the drive shaft which is equipped with the gear 38 while interposed between the gear and the ring gear 39 on the 40 inside of the rotor 6 are the planetary gears 40.

As can be seen in Figures 4 and 5, the inner sides of the walls 9—10 are provided each with an annular arrangement of pockets 50 with which the ducts 51 extending downwardly and laterally 45 from the pockets 15 register. Thus the fluid pressure can be supplementarily used to afford a turbine effect between the rotor and stator.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A rotary engine comprising a stator, a rotor rotatably mounted within the stator, said rotor being provided with a plurality of pockets in its periphery, a plurality of radially slidable abutments on the stator, spring means for urging said abutments inwardly and against said rotor, the inner ends of the abutments being adapted to ride into the pockets, and means for supplying compressed fluid into the pockets at one side of the abutments to cause movement of the rotor

in a given direction, said rotor having curved passages therein, one for each pocket, each passage having one end in communication with the rear end of a pocket and its other end opening out through a side part of the rotor and the adjacent side of the stator having a plurality of grooves therein for communicating with the passages during a portion of the rotary movement of the rotor and exhaust means connected with said grooves.
